UNITED STATES PATENT OFFICE.

ARTHUR P. SMITH AND SAMUEL EICHEL, OF NEW YORK, N. Y., ASSIGNEES TO HAR-
VARD AUTO BODY COMPANY, INC., A CORPORATION OF NEW YORK.

AUTOMOBILE BODY.

Application filed August 2, 1926. Serial No. 126,502.

The object of the present invention is to provide a closed automobile body which will have the advantages of both the sedan and laundalet types of bodies, without the disadvantages of either.

The invention will be understood by reference to the accompanying drawing in which—

Figure 1 is a view in elevation of that portion of an automobile body, to which the invention is applied;

Figure 2 is a similar view from the rear, and

Figure 3 is a view in plan and partial section of a form of fastening or connecting means which may be employed in the device.

In the drawing we have shown the rear of a closed body A having a rigid top 1 and an intermediate horizontal frame or molding 2.

In the present embodiment there is provided at each side of the body intermediate the horizontal frame member 2 and the top 1 a rigid side panel 3 which may be provided with a window 4.

In the usual laundalet the top is sectional and hinged in such manner as to be swung rearwardly, the flexible leather vertical walls intermediate the rearwardly swinging portion of the top and the main body portion collapsing in such movement. While a laundalet possesses certain advantages in summer weather, it possesses decided disadvantages which have greatly restricted its general adoption. One disadvantage resides in the fact that the top must be formed into two sections, so that the rear section may be swung downwardly with the connected collapsible side and rear panels, requiring special means for supporting and locking it in closed position and for making it water tight.

In the present invention the top 1 may be rigid throughout. Extending vertically from the frame or molding 2 and thence horizontally along the base of the top 1 is a joint which serves to connect the side panels 5 and the rear panel 6 to the top and to the rigid side panels 3. Means such as snap fasteners of well known construction, indicated diagrammatically at 7, may be employed for securing panels 5 and 6 to the molding or frame 2.

When the panels 5 are disconnected from the body, as also the rear panel 6, the body will be converted from a sedan or limousine, as the case may be, into a laundalet, with the advantage, however, that the top 1 remains

rigid throughout and affords a shade member for the occupants of the rear seat of the vehicle.

One of the important features of our invention is the provision of a joint-device which will enable the ready joining or disjoining of the panels and body.

In practice the panels 5 and 6 may be of leather or other flexible material, although it is not absolutely required that they be of such construction. At their meeting edges, however, they will preferably be provided each with a flexible connection, such as a tape, to which tape will be secured a length of contiguous fastening members complementary to the fastening members on the tape of an adjacent panel. The fastening members, when connected, form the joint.

In Figure 3 we have illustrated a suitable form of joint. 5 indicates one of the panels and 7 a tape secured thereto. Clamped upon the tape are a plurality of adjacent parallel fastening lugs 8 which are complementary to a plurality of fastening lugs 9 on a tape 10 connected to the panel indicated at 6. At 11 is indicated a sliding cam device having angularly arranged opposed walls and adapted to embrace the fastening lugs when they are moved into substantial contact and to bring them together in such manner that the projection 9^x of one fastening member will enter the socket of an opposite fastening member. Upon a reverse movement of the cam member it is adapted to disengage the lugs. We make no claim to a fastening device per se, it being the subject of an issued United States Patent.

It will be noted that the parallel fastening members at 9 on the panel 6 do not extend beyond the inlet or opening of the cam member 11 when the two panels are separated, whereas the strip of fastening members on panel 5 is of greater length and terminates in a stop member indicated at 11^x so that the cam member remains attached to panel 5 when the panels are disjoined. In joining the panels, panel 6 is moved toward panel 5 until one end of the strip of fastening members comes into register with the inlet of cam member 11. That member is then moved in a direction to forcibly bring the fastening members 9 into register with the fastening members 8 and finally into interlocking relationship.

We have shown a single cam member 11 for

joining and disjoining the panels 5 and 6 relatively to the top 1 and side panels 3. From its position, as shown in Figure 1, cam member 11 may be moved upwardly and thence 5 horizontally to its extreme right hand position at the front end of the opposite panel 5 whereupon both panels 5 and panel 6 will be disconnected from the body except at their points of connection through snap fasteners 10. If it is desired to remove only the panel 6 cam 11 will be moved from its position in Figure 1 upwardly and thence to the right beyond the end panel 6 and the corresponding cam members 11 will be moved downwardly to disconnect panels 5 and 6 as heretofore explained with reference to Figure 3. It will be understood that cam member 11 15 will remain permanently connected to a tape which is secured to the rear edges of panels 20 3 and to the top member 1.

Having described our invention what we claim and desire to secure by Letters Patent

is as follows, it being understood that the joint device illustrated in Figure 3 may be substituted by other forms of joints having 25 the same general function, without departing from the spirit of the invention:

A passenger automobile body of the laundry type having a rear door opening on each side, a horizontal frame rearwardly of the door openings, a rigid top, a side rigid member connecting the top and horizontal frame rearwardly of each door frame, and a plurality of flexible panels in combination with interlocking means at their marginal edges 30 and co-acting interlocking means therefor at the rear edge of each of said side rigid members and at the said rigid top and extending horizontally thereof, as and for the purpose 35 described.

In testimony whereof, we have signed our names to this specification.

ARTHUR P. SMITH.
SAMUEL EICHEL.
